UNITED STATES PATENT OFFICE.

PAUL J. BROWN, OF NORTH OLMS TED, OHIO.

WINDOW CONSTRUCTION.

Application filed July 30, 1923. Serial No. 654,665.

To all whom it may concern:

Be it known that I, PAUL J. BROWN, a citizen of the United States, and a resident of North Olmsted, county of Cuyahoga, 5 and State of Ohio, have invented a new and useful Improvement in Window Construction, of which the following is a specification, the principle of the invention being herein explained and the best mode in 10 which I have contemplated applying that principle so as to distinguish it from other inventions.

This invention relates to an improved window construction. More particularly it 15 comprises a window construction having guide members co-operating with grooves formed in the sash whereby a window installation of few parts and simple construction is provided and one which at the same 20 time is rattle-proof and a full protection against the weather.

In addition to being constructed of a relatively small number of parts, the window sash, guide members and latching device 25 have been found to be of extremely durable character and to work well when subjected to severe usage, as in automobile busses.

Heretofore metal window sashes, particularly designed for use in vehicles, have included 30 guide members with additional resilient devices to make the structure weather-proof and to provide against vibration and noise. Such constructions have been relatively expensive and require very accurate 35 application to the window frames to prevent such windows from becoming inoperative and jamming when subjected to rough usage.

The principal object of the present invention 40 is to simplify window constructions, particularly metal window constructions, for use upon vehicles and to include as integral parts of the guide strips themselves a resilient construction which will serve to 45 prevent vibration and noise and at the same time provide a small degree of flexibility which will compensate for slight errors in accurate alignment of the parts. A further object of the invention is to so form a single 50 strip of sheet metal as to provide the same with a rack section, frame engaging elements, a beaded guide member and a resilient portion so that a multiplicity of parts is avoided and yet every necessary function 55 of said guide and fastening element provided for. Other objects of the invention

will appear in the course of the following description.

The window as illustrated embodies features particularly adapting it for use in auto 60 bus bodies, railway cars and street cars, but it is to be understood that such showing is not intended in any manner to limit the scope of the invention as set forth in the 65 claims. To the accomplishment of the foregoing and related ends, said invention, then, consists of the means hereinafter fully described and particularly pointed out in the claims.

The annexed drawing and the following 70 description set forth in detail certain mechanism embodying the invention, such disclosed means constituting, however, but one of various mechanical forms in which the principle of the invention may be used. 75

In said annexed drawing:—

Fig. 1 is a front elevation of the window sash and guides applied to a window frame; Fig. 2 is a horizontal sectional view showing a frame member between adjacent windows with the attached guides and channeled strips; Fig. 3 is a fragmentary side elevation of one of the guide members; Fig. 4 is a vertical central sectional view showing the top and bottom members of the 80 sash with the rubber cushion strips inserted therein; and Fig. 5 is a horizontal sectional view similar to Fig. 2 showing a curtain 85 guide strip applied to the window frame.

As is clearly shown in the drawing, the 90 window comprises a sash 1, preferably formed of sheet metal provided with grooves 2 at each of its vertical sides, said grooves being of slightly more than semi-circular transverse section in order to partially embrace 95 the beaded edge of the guide members hereinafter to be described. The frame may be built up of pressed metal strips appropriately channeled on one side to engage the glass of the window and provided upon the 100 opposite edge with grooves of somewhat more than semi-circular transverse sectional extent. These grooves 3 on the upper and lower sides of the window sash are adapted to receive rubber cushion strips 4, 5, having 105 a rib or bead 6 of somewhat more than semi-circular extent upon one side. Where applied to the under side of the sash the outer face of such strip is appropriately shaped 110 to engage the adjacent sill 7, and when applied to the upper side of the sash of the window frame such strip is suitably formed

to serve as a weather-strip against the stationary part adjacent the upper edge of the window when the same is in closed position. (See Fig. 4.)

5 These channeled strips may be mitred at their ends and joined in any preferred manner, as by brazing, spot-welding or otherwise. When the device is to be used upon a vehicle such as a motor bus, there is preferably provided adjacent each of the lower corners of the sash upon the inner side of the window a pair of latch members comprising a stationary body plate 11 adapted to be secured to the frame and provided with 10 an inwardly projecting finger piece 12, and a dog 13, provided with an integral finger piece 14 pivotally mounted upon said plate and held in projected position by means of a spring 15 coiled about said pivot pin 16 and engaged at its ends with said plate and dog, respectively.

The guide members which, as has been indicated, co-operate to engage with the grooves at each side of the sash, are preferably sheet-metal strips 21 of a length approximately twice the height of the window sash. These strips are provided at one edge with a bead 22 of substantially circular cross-section formed by wrapping said 25 edge about a metal bar 23 of small diameter. The opposite edge of said strip is provided with a flat marginal portion 24, into the lower portion of which a series of rack teeth 25 are impressed to co-act with the 30 dogs of the latches heretofore referred to. A series of holes for fastening screws 26 are provided, such holes being placed at intervals throughout the length of the strips and between the rack teeth to provide means 35 for securing said strips to a wooden window frame. When the strips are to be secured to a metal window frame, suitable bolts may be used at intervals along said strip.

In the construction illustrated the flat 40 portions of the strips are secured to the inside of the window frames and said strips are provided with a curved or bent portion 31 formed along a line between said flat portions and the beaded edge heretofore referred to, in order that said beaded edge may 45 project at substantially right angles to said flat portion; when so formed, the curved portions 31 of the strips are spaced a slight distance from the window frame and said intermediate portion thus acts as a resilient or spring support for the window sash, preventing vibration and noise, and through the resiliency and flexibility of said part preventing jamming or interference with 50 the free sliding motion of the window.

As has been indicated, the rack portions of the strips are adapted to be engaged by the projecting ends of the dogs when the sash is in place upon the beaded edges of the 55 guide members. By grasping the finger pro-

jections upon the plate and dog of the latch at either side of the window, the dogs may be retracted and the window shifted to the position desired, whereupon the release of said finger pieces will permit the re-engagement of said dogs with the adjacent rack teeth.

As is clearly shown in Figs. 2 and 5, when the device is applied to a vehicle such as a motor bus, it may be found desirable to place upon the outside of each frame member 30, between the adjacent windows, a flanged metal channel member 32 of a size adequate to embrace said frame member and position said flanges 33 in slightly spaced relation to the outside of said outside surface of the sides of the sash. Upon the inside of said frame member a wooden strip 34 may be fastened, said wooden strip being channeled on its inner face so as to permit its lateral edges to overlap the edges of the flat portions of the guide strips secured to the opposite sides of said frame member. Thus, when the window construction is fully assembled, a complete and finished appearance will be produced.

When it is desired to provide for curtains at the windows, a sheet metal strip 41, formed with a flat outer surface and lateral guide grooves 42 at each side and a wide channel-way 43 upon its interior face between said lateral guide grooves, may be secured to the inside of said frame members in place of the wooden member heretofore referred to.

From the above description it will be apparent that the window construction provides a simple, durable structure capable of being easily applied to the window frame and adapted to serve as an adequate protection against the weather, as well as to withstand severe handling when the window is raised or lowered. These features are of particular importance when the construction is used upon vehicles, such as auto busses, street cars and railroad coaches, especially the providing of a free, resilient section as an integral part of each guide strip. Said construction is also adaptable for use on boats and may be applied to houses and cottages where light weather-proof construction is found desirable.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In an article of the class described, the combination of a window sash, a groove formed in each vertical edge thereof, said groove being of enlarged cross-section at

- its inner portion, and a pair of vertical guide members formed of sheet metal strips adapted to be attached to the window frame, each of said strips being provided with an intermediate resilient section connecting its base with an enlarged edge angularly disposed with respect to said base and adapted to engage within the enlarged portion of the adjacent groove of the sash, each strip co-acting with its companion strip to resist motion of said window sash transversely in the plane of the sash and laterally with respect thereto.
2. In an article of the class described, the combination of a window sash, a groove formed in each edge thereof of slightly more than semi-circular transverse section, a pair of guide members formed of sheet metal strips adapted to be attached to opposite sides of the window frame, each of said strips being provided with an intermediate resilient section connecting its base with an enlarged edge angularly disposed with respect to said base and adapted to engage within the adjacent groove of said sash to resist motion of said window sash transversely in the plane of the sash and laterally with respect thereto, and rubber cushion strips provided with ribs of somewhat more than semi-circular extent upon one side seated within the intermediate grooves of said window sash.
3. In an article of the class described, the combination of a metal window sash, a groove formed in each vertical edge thereof, and a pair of vertical guide members formed of sheet metal strips, each of said strips being provided with a beaded edge resiliently connected with said body portion and adapted to engage said grooves, and said body portion of the strip being provided with means for securing said strip to the casing of the window, and with integral means co-operating with means upon said sash to hold said window in elevated position.
4. In an article of the class described, the combination of a metal window sash, a groove formed in each vertical edge thereof, spring pressed latches secured to the lower portion of said sash adjacent to each side thereof whereby a pair of dogs are adapted to be projected laterally, a pair of vertical guide members formed of sheet metal strips, each of said strips being formed with a flat portion and a beaded edge, said flat portion being shaped to provide a series of teeth adapted to be engaged by the dogs of said latch members, and the beaded edges of said strips being adapted to engage said grooves of said sash and being angularly disposed with respect to said flat portion of the strips and supported in resilient relation thereto.
5. In an article of the class described, the combination of a metal window sash, a groove formed in each vertical edge thereof, spring pressed latches secured to the lower portion of said sash adjacent to each side thereof whereby a pair of dogs are adapted to be projected laterally, a pair of vertical guide members formed of sheet metal strips, each of said strips being formed with a flat portion and a beaded edge, said flat portion being shaped to provide a series of teeth adapted to be engaged by said dogs and also being provided with means for securing the same to the adjacent window casing.
6. In an article of the class described, the combination of a frame member adapted to be positioned between two adjacent windows, a pair of window sashes having grooves formed in their vertical edges, a pair of guide members formed of sheet metal strips attached to each side of said frame member, each of said strips being provided with an intermediate resilient section connecting its base with a guide edge angularly disposed with respect to said base and adapted to engage within the adjacent groove of the adjoining window sash to resist motion of said window sash transversely in the plane of the sash and laterally with respect thereto, a flanged metal channel member fitted over the outer portion of said frame member with its flanges in spaced relation to said respective window sashes, and a channeled strip fitted to the inner face of said frame member with its flanges overlying the edges of the flat portions of said sheet metal guide strips.

Signed by me, this 23rd day of July, 1923.

PAUL J. BROWN.
